TRIPLE VALVE.

No. 833,965.

Specification of Letters Patent.

Patented Oct. 23, 1906.

Application filed June 28, 1906. Serial No. 323,938.

To all whom it may concern:

Be it known that we, DAVID INCHES, residing at the town of North Bend, and EDWARD J. HOSKER, residing at the city of Kamloops, in the Province of British Columbia, Canada, citizens of the Dominion of Canada, have invented a new and useful Improvement in Triple Valves, of which the following is a specification.

- 10 This invention relates to an improvement in the triple valve which in an air-brake system such as the "Westinghouse" or "New York" operates to admit the compressed air from the auxiliary reservoir to the brake-cylinder, which triple valve is actuated for either a "service" or an "emergency" application by a slight or greater reduction of the pressure in the train line-pipe, as either one stop or the other is required.
- 15 This invention is designed to remove the possibility of an emergency application occurring when the pressure of the train-pipe is only reduced slightly for a service application. This fault is caused by undue friction of the 20 triple-valve piston or its connected parts on any particular vehicle, caused by gummy oil or dirt, which will hold the piston and prevent it responding freely to the slight service reduction of pressure requisite to operate it.
- 25 If this undue friction in any particular triple valve would only prevent the service application of pressure being admitted to the brake-cylinder of its own vehicle, the objection would not be very serious. Owing, however, to the uncertainty of the frictional resistance of a dirty triple valve the piston may be held back while a service reduction is being made, and then breaking free will respond suddenly to the reduction and will overrun 30 the limit of the movement necessary to operate the valve for a service application and may pass to the full limit of its movement and operate an emergency-stop, not only on its own vehicle, but on all the vehicles of the train.
- 35 This defect is one the objection of which has long been experienced and a remedy for which has been carefully sought for. We propose to overcome it by providing a means by which when any triple-valve piston fails to respond 40 to a slight reduction of pressure in the train line-pipe the air from the auxiliary-reservoir side of the piston will pass to the train-line side. In other words, if a triple valve will not respond to a slight or service reduction

of pressure we propose to deprive it during 55 that particular reduction of the means for operating at all in a service-stop, while its full power is still available for an emergency-stop when necessary.

The essential feature of this invention, 60 therefore, lies in providing a means for passing air under a certain measure of control, which will be explained, from the auxiliary-reservoir side of the triple piston to the train-line-pipe side when such piston does 65 not respond to a service reduction or pressure in the train line-pipe. The manner in which we propose to effect this purpose is fully set forth in the following specification, reference being made to the drawings, by which it is 70 accompanied, in which—

Figure 1 is a longitudinal section through a triple-valve body, showing in full lines the piston in the normal or feed position and in dot-and-dash lines its position during a service-stop. Fig. 2 is a similar view showing the position of the piston during an emergency-stop, and Fig. 3 a cross-section through the outlet-port on the line A.

In the drawings, 2 represents the body of 80 the triple valve, 3 the triple-valve piston, and 4 its ring, 6 being the train-line side of the piston, and 5 the auxiliary-reservoir side.

A passage 10, shown in the drawings for convenience of illustration as a pipe, leads 85 from a convenient position on the auxiliary-reservoir side 5 of the triple-valve piston and delivers through a narrow circumferentially-elongated port 11 in the bushing of the triple-valve cylinder on the train-line side of 90 its piston 3 when this piston is in the normal or feed position.

The passage 10 is furnished with a check-valve 12, opening toward the train-line-pipe side, which check-valve is spring-loaded to 95 an amount slightly in excess of the maximum pressure necessary to cause a movement of the triple-valve piston when such is clean and in good working order. With this provision if from any reason, such as gummy oil or dirt, the piston of a particular triple valve of the train does not respond freely to a service reduction of pressure in the train line-pipe the excess of pressure which should operate its piston 3 to admit air to 105 the brake-cylinder will pass through the passage 10 to the train-line side of the piston 3 and preclude the possibility of such excess

pressure operating the piston during the stop and possibly causing the piston to overrun the limit for a service-stop and operate its own and consequently other triple valves 5 for an emergency-stop.

- In order to avoid air passing through the passage 10 when the triple piston is working properly and responds freely, the location of the port 11 and its width are such that it will 10 be covered by the ring 4 of the piston 3 when the piston end 7 first contacts with the end 8 of the graduating-stem, but that on further movement of the piston to compress the graduating-stem spring 9, as in an emergency-stop, the piston will pass the port 11, and as both inlet and outlet of the passage 10 will then be on the auxiliary-reservoir side of the piston no air will be able to pass through it from the auxiliary reservoir to the train-line side of the piston 3. It is further desirable that the port 11 will be uncovered to the train-line side of the piston when the piston 3, as in a service-stop, moves back off the end of the graduating-stem 7 to close the graduating-valve of the triple-valve slide 13. This is necessary to insure that if the piston of a dirty triple valve which may have responded to a first reduction of pressure for a service-stop refuses to respond to a further reduction 25 30 35 40 45 50
- the excess of pressure which would operate a triple valve in good order will pass through the port 11 to the train-line side of the piston 3 and avoid the possibility of the piston being suddenly released and setting the brakes for an emergency-stop. In applying the invention to the existing Westinghouse triple valve the port 11 cannot be exactly located as described, because of the limited width of the piston-ring, and in such application of the invention the port is, strictly speaking, located approximately half-way in the travel of the piston-ring 3 from its position when the piston end 7 is in first contact with the end 8 of the graduating-stem and the position of said ring when the graduating-valve of the slide 13 is closed and before the slide-valve itself is moved. It will be apparent that this passage 10 and the control of its outlet or inlet by the movement of the triple-valve piston 55 60 65 is the essential feature of this invention.

In the operation of the device, when a service-stop is to be made and the triple-valve piston moves freely a sufficient amount to admit air to the brake-cylinder through the graduating-valve of the slide-valve 13 of the triple air cannot pass through the passage 10, as such passage is closed against such slight reduction by the pressure of the spring which maintains the check-valve 12 on its seat; but if the triple valve is dirty and the piston of it is held back by the undue friction caused by the presence of such dirt any excess of air-pressure over what is necessary to move a piston in good working order will 65 press open the check-valve 12 and the air

will pass through the passage 10 from the auxiliary-reservoir side to the train-line side of the piston 3 and will prevent that excess of air-pressure acting on the piston 3, as it might do, to cause an emergency-stop if the 70 gummy oil or dirt which held the piston back in the first instance should release it later; but although we propose to thus automatically deprive a dirty or gummed-up triple valve of the means to do harm, in causing an 75 emergency-stop when such is not required, if such stop is necessary the sudden and extreme reduction of pressure required to effect such will move the piston 3 to the full limit necessary to operate the emergency-valve, 80 and in that movement the piston-ring 4 will pass the port 11 in the triple-valve cylinder, so that both ports of the passage 10 are on the auxiliary-reservoir side of the triple piston and the passage 10 can have no effect. 85

With this invention not only is a means provided to prevent a dirty triple valve from disarranging a service application of the brake on the whole train, but it will by the non-application of the brake on that vehicle enable the defective triple to be located, and, if considered desirable, it can at once be cleaned before proceeding. 90

It will be obvious that the particular device illustrated necessitates no alteration or 95 modification of the essential principles of action of the triple valve, but is merely a supplementary provision that when through the presence of dirt or gummy oil a triple-valve piston does not respond readily to the reduction of air in the train line-pipe that should operate such piston to effect a service-stop will enable the excess of air on the reservoir side of the piston to pass to the train-line side of the same and obviate the possibility of that excess operating the piston during the service-stop to set an emergency application. 100 105

We are aware that prior to our invention provision has been made in triple valves to 110 admit air past the piston which operates the slide-valve, but such is only when that piston is in the position of release or feed, and is closed as soon as the piston has moved far enough to open the graduating-valve of the 115 slide and before it moves the slide itself.

What we therefore claim as new, and desire to be protected in by Letters Patent, is—

1. In a triple valve of the class described; a passage through which air may pass from the auxiliary-reservoir side of the triple-valve piston when such is in the normal or feed position to the train-line side of the same, and means for closing such passage by any movement of the triple-valve piston 120 125 that would move the slide-valve thereof.
2. In a triple valve of the class described; an air-passage from the auxiliary-reservoir side of the triple-valve piston when such is in the normal or feed position to the train-line 130

side of the same, said passage terminating in a port in the triple cylinder the location of which is such that it will be closed by the ring of the piston when such piston is in first contact with the adjacent end of the graduating-stem and that will be open to the train-line side of the piston when the piston moves back to close the graduating-valve of the slide.

3. In a triple valve of the class described; an air-passage from the auxiliary-reservoir side of the triple-valve piston when such is in the normal or feed position, to the train-line side of the same, such passage terminating on the train-line side in a port in the wall of the triple cylinder, the location of which port is such that it will be closed by the ring of the piston against passage of air from the train-line side of the graduating-stem, and that will be uncovered toward that side when the piston moves back the amount necessary to close the graduating-valve of the triple slide.

4. In a triple valve of the class described; an air-passage from the auxiliary-reservoir side of the triple-valve piston when such piston is in the normal or feed position to the train-line side of the same, the outlet of such passage on the train-line side being such in location and width that it will be closed by the ring of the piston when such piston is in first contact with the adjacent end of the graduating-stem but will be open to the train-line side of the piston when the piston has moved back off the graduating-stem a sufficient amount to close the graduating-valve of the triple-valve slide, means for preventing the passage of air through such passage from the train-line side to the auxiliary side of the piston, and means for preventing the passage of air through such passage from the

auxiliary-reservoir side of the piston to the train-line side until a predetermined difference of pressure has been attained.

5. In a triple valve of the class described; an air-passage from the auxiliary-reservoir side of the triple-valve piston when such is in the normal or feed position to the train-line side of the same, the outlet of which passage on the train-line side of the piston is so located that it will be closed when the piston is in first contact with the graduating-stem, but opened to the auxiliary-reservoir side of the piston with any further movement that would compress the graduating-spring, a check-valve in such passage that will prevent the passage of air therethrough from the train-line side to the auxiliary-reservoir side of the piston, and means for leading such check-valve that it will not open until a pressure exists on the auxiliary-reservoir side of the piston slightly over what is required to operate the triple-valve piston and its slide when such are in good working condition.

6. In a triple valve of the class described, a conduit through which air may pass from the auxiliary-reservoir side of the triple-valve piston when the same is in one position to the train-line side of the piston, and means for controlling the passage of air through said conduit to the train-line side of the piston as the piston moves to move the slide-valve thereof substantially as shown and described.

In testimony whereof we have signed our names to this specification in the presence of two subscribing witnesses.
